UNITED STATES PATENT OFFICE.

RICHARD H. TYNER, OF CINCINNATI, OHIO.

BOOTH FOR CLASSIFYING, MARKING, AND ENUMERATING LAUNDRY.

1,295,641.

Specification of Letters Patent. Patented Feb. 25, 1919.

Application filed June 12, 1916. Serial No. 103,315.

To all whom it may concern:

Be it known that I, RICHARD H. TYNER, a citizen of the United States, and resident of Cincinnati, in the county of Hamilton and State of Ohio, have invented a certain new and useful Booth for Classifying, Marking, and Enumerating Laundry, of which the following is a specification.

The object of my invention is to provide a booth of simple, durable and inexpensive construction, especially adapted for use by laundry workers in sorting, marking and enumerating articles of laundry.

Still a further object is to provide such a booth which may be readily and easily taken apart or set up, and which is of comparatively light weight, so that it may be easily moved from place to place, and is so constructed that laundry workers may work therein and be free from interference by others; the booth being provided with a suitable shelf for sorting laundry, and with means comprising part of the side wall of the booth, whereby seclusion is afforded, and means provided for enumerating and classifying different kinds of laundry articles.

My invention consists in the construction, arrangement and combination of the various parts of the device, whereby the objects contemplated are attained, as hereinafter more fully set forth, pointed out in my claims and illustrated in the accompanying drawings, in which:

Figure 1 shows a perspective view of a booth embodying my invention.

Fig. 2 shows an enlarged, detail view of the inner surface of one of the walls of the booth.

Fig. 3 shows a longitudinal, vertical, sectional view of said booth.

Fig. 4 shows a top or plan view of the same.

Fig. 5 shows an enlarged, detail, plan view of the portion of the wall illustrating the hooks thereon, and

Fig. 6 shows an enlarged, detail, side elevation of a small portion of said wall.

My improved booth comprises an article of manufacture, peculiarly adapted for facilitating and reducing the amount of work done in laundries, and insuring greater accuracy and fewer losses in the handling of laundry articles.

It may help in the following explanation of my invention to briefly mention a common method of handling laundry work.

One person opens the bundle and sorts the different classes of laundry articles. A second person counts the articles in each class and either lists them on a sheet of paper, or calls them out to another person who lists them. The articles are then all passed to a marker. The possibilities of errors, due to such a system of handling laundry, are obvious.

My improved booth comprises spaced upright posts 10 arranged at the rear corners of the booth and preferably made of pipe.

Spaced forwardly from the upright members 10 are intermediate upright members 11 preferably arranged substantially midway of the booth. The upper ends of the members 10 are connected by a suitable cross member 12 comprising a pipe connected with the members 10 by ordinary fittings 13. The upper ends of the members 11 are connected by a similar pipe 14 and similar fittings 15.

Forwardly of the members 11 are spaced upright members 16 which are shorter than the members 11 and form the forward corners of the booth. The members 16 comprise pipes and are connected at their upper ends with forwardly extending shelf supporting members 17 connected to the uprights 16 by suitable elbows 18.

Resting upon the members 17 is a bundle shelf 19.

At a suitable height considerably below the upper ends of the members 11 and 10 and spaced from the lower ends thereof, the members 11 and 10 on the opposite sides respectively of the booth, are connected by a pipe 20 and suitable fittings 21. Each member 11 is connected by a similar pipe 22 with one of the members 16. The members 10, 11 and 16 are set at their lower ends in sockets 23 having the ordinary floor flanges which may be secured to the floor of the room where the booth is located.

Resting upon the pipes 22 is a laundry receiving shelf 24 preferably lower than the shelf 19. Above the ends of the shelf 24 are windows 25 to admit light and to complete the walls of the booth.

On one end of the shelf 24 I have mounted an ordinary laundry marking machine 26, Fig. 3.

Below the pipe frame members 20 and 22, at the sides of the booth, are wall sections 27 of reticulated material, and below the shelf 19 are somewhat longer higher sections 28, whereby the lower part of the booth is in-

closed on three sides. The rear part of each booth may be open if desired.

Below the shelf 24 is a longitudinally arranged partition wall 29, and a transverse 5 partition wall 30, the latter being spaced horizontally below said shelf, which walls 29 and 30 with the adjacent walls 28 and 27 form a receptacle for wrapping paper and the like.

10 The screen sections, hereinbefore referred to, are detachably mounted upon the frame members by wire loops 31 or any other suitable means.

It will be noted that the fittings 13 and 15 are the ordinary T's, whereby another booth 15 could be connected with the one now being described and the partition wall between the two booths could be common for both of them.

20 The members 10 and 11 on each side of the machine near their upper ends are connected by frame pipe members 32 and fittings 33.

The walls of the booth on each side therefore 25 of between the members 10 and 11 and the members 20 and 32, are of peculiar construction, and comprise means having a wall for inclosing a portion of the booth, and also what might be called an enumerating and 30 counting portion or member.

In the form of the device shown in the accompanying drawings, I have shown each of said wall portions made of a plurality of inwardly, opening channels having the central 35 vertical members 34, the flanges 35, arranged at right angles to the central members 34, and the laterally extended flange 36 at the inner edge of each flange 35.

The channels are arranged side by side in 40 each wall, with the flanges 36 of adjacent channels abutting against each other.

The successive channels are connected together by means of strips or bars 37, which may be secured to the frame of the booth in 45 any suitable way.

Mounted between the flanges of the various channels is a plurality of laundry holding hooks, the construction of which is shown in Figs. 5 and 6. Each hook comprises, what I may for convenience' sake call, an upper and a lower hook member. The upper hook member comprises a downwardly extended U-shaped portion 38.

At their upper ends the arms of the portion 55 38 incline at 39 toward the booth wall to position adjacent to the flanges 35 of one of the channels. At the upper end of each arm 39 is a laterally extending portion 40, rotatably mounted in one of the flanges 35.

60 The lower hook member is of similar construction to the upper hook member just described, having a downwardly extending U-shaped portion 38^a with the opposite arms 39^a extending toward the wall and having 65 at their outer ends the laterally extending

portions 40^a rotatably mounted in the flanges 35 of the channel at points below the portions 40. The arms 39^a are provided with portions 41 curved upwardly over the arms 39, whereby the lower hook member is slidably mounted on the arm 39 of the upper hook member. The parts of the hook just described are so constructed and arranged that when the hook members are raised, the portion 38 will stand above and away from 75 the portion 38^a, so that a piece of laundry can be inserted between said portions. When the hook member is then turned downwardly, the piece of laundry will be firmly gripped between the members 38 and 38^a. 80 The hooks of each channel are conveniently arranged in vertical succession, and the channels are provided with indicating numerals or the like 43, Fig. 2, preferably running in numerical succession from 1 upwardly and beginning at the lower end of the channel, so that the lower hook of each channel is 1, the next upper hook 2, and so on.

On the upper part of each channel there 90 may be provided indicating characters as shown for showing the kind of laundry articles hanging on the hooks of that channel.

It will thus be seen that the hooks are arranged in vertical columns, and that each 95 column has its appropriate characters for listing.

In the practical use of my improved laundry booth the wrapped bundles are placed upon the shelf 19. The operator within the 10 booth moves one bundle from the platform 19 to the platform 24, where the wrapping material is removed and may be thrown into the receptacle therefor, above referred to.

The operator then sets the proper marking 10 characters on the machine 26, and marks each article as it is taken from the pile on the platform 24. Each bundle is handled as a unit, and is completed before another bundle is touched.

There is, therefore, no danger of mingling one person's laundry with that of another.

After the article is stamped on the marking machine, the operator hangs it on the lowest unoccupied hook of the appropriate 1 column. That is to say, for instance, the first shirt taken from the bundle is marked and then hung on the lower hook, being hook number one in the column for shirts, on that portion of the wall of the booth which forms 1 the sorting and enumerating board.

When the marking and sorting and hanging of the articles in the bundle is completed, the operator may take the printed list and by glancing at the number above the last occupied hook of each column, can in an instant determine how many laundry articles of the class indicated by that column are included in the bundle.

The listing may be quickly and easily com- 1

pleted. When this is done, all of the articles may be removed from the counting board and thrown into laundry baskets, carts or the like.

5 Some changes may be made in the construction and arrangement of the parts of my improved device without departing from its essential features and purposes, and it is my intention to cover by this application 10 any such changes which may be included within the scope of my claims.

I claim as my invention:

15 1. A laundry booth comprising an inner rear shelf, an upper forward and higher shelf, a forward wall extending below the second named shelf, and above and below the forward edge of the first named shelf, and

side walls equipped with means for detachably holding different classes of laundry articles.

20

2. A laundry booth comprising an inner rear shelf, an outer forward and higher shelf, a forward wall extending below the second-named shelf and above and below the forward edge of the first-named shelf, and 25 side walls; the said side walls having window portions above the end portions of the first-named shelf and also having in rear of said window portions, upright portions equipped with means for detachably holding different classes of laundry articles.
